UNITED STATES PATENT OFFICE.

CHARLES M. LOEPFE, OF ST. LOUIS, MISSOURI, ASSIGNEE TO COTTONWOOD FIBER COMPANY, OF ST. LOUIS, MISSOURI, A CORPORATION OF MISSOURI.

OIL BURNER.

Application filed March 2, 1925. Serial No. 12,597.

This invention relates to improvements in oil burners, and consists in the novel construction hereinafter disclosed.

An object of the invention is to provide a burner that is compact in form and designed as a portable oil burner, equipped with means for initially heating the gas to start the operation of the burner.

Another object of the invention is to improve the means for preheating the vaporizer by deflecting the flame directly against and into contact with the walls of the vaporizer.

Additional advantages of the construction will be apparent from the following detailed description thereof taken in connection with the accompanying drawings, in which—

Fig. 1 is a plan view of the burner.

Fig. 2 is a front elevation.

Fig. 3 is an end view.

Fig. 4 is a vertical section on the line 4—4 of Fig. 2.

Fig. 5 is an end view opposite the view in Fig. 3.

Fig. 6 is an end view of the baffle wall construction for deflecting the flame against the vaporizer.

Fig. 7 is a front view of the same part.

In the embodiment of the invention illustrated in the drawing the heater is shown as including a base casting comprising end walls 1 and 2 having inwardly extending horizontal flanges 3 and a back wall 4, said back wall having an inwardly turned upper margin 5 in which are spaced notches 6. The side faces of the upper part of the wall 4 have attached thereto strips 7 of asbestos or other non-heat radiating material which prevent the radiation of heat from the wall. The flanges 3 are arranged to support a trough or pan 8 from the front wall of which extends a channeled projection 9 that constitutes a handle for withdrawing the pan 8 and also as a runway for pouring a combustible fluid, such as alcohol, into the pan from the front of the heater.

The gas chamber of the heater comprises a hollow casting having a cylindrical portion 10 and an irregularly shaped portion including a vertical front wall 11, a rounded bottom wall 12, an inclined back wall 13 and a horizontal upper wall 14. One end of the portion 10 is provided with a flange 15, and the opposite end with a cylindrical extension 16 having a vertically extending notched

bracket 17. This casting is mounted upon and supported by the end walls 1 and 2 of the base casting.

The upper wall 14 of the gas chamber is provided with parallel series of openings 18 and 19 in which perforated discs 20 and 21 are fitted, the discs 20 and 21 being made of any suitable non-combustible material. The openings 19 are spaced in the wall 14 so that they are alined with the center of the notches 6 when the parts are assembled, and the openings 18 are formed in a longitudinal series forward of said openings 19.

Along the front edge of the wall 14 is a vertical flange 22, and mounted against the flange and in alinement over the openings 18 are frames 23 of radiant refractory material within the limits of which the gas emitted through the discs 20 is burned, the frames 23 assisting in the radiation of the heat and in imparting to the burner a radiant appearance.

Attached to the flange 15 is an air mixer that includes a plate 24 and a rounded hollow extension 25 that has an opening that registers at one end with the opening at the end of a cylindrical portion 10 of the gas chamber, and into the opposite end 26 the end of the vaporizing tube is fitted. The extension 25 has on either side an opening 27 to atmosphere for the admission of air to be mixed with the vapor emitted from the vaporizing tube. The vaporizing tube 28 is supported transversely across the openings 19 in the top wall of the gas chamber and is equipped with a tip 29 that enters the opening in the part 25. The opposite end of the vaporizing tube 28 is supported in the notch in the bracket 17 and the position of the portion of the vaporizing tube that lies over the openings 19 is such that the upper edge 5 of the wall 4 turns forwardly over the upper face of the tube. The notches in the wall 4 provide a sufficient area for the admission of air to the flame emitted from the discs 21 and also provide passage ways through which the flame from the combustible fluid in the pan 8 can find egress and at the same time hold the flame in close contact with the vaporizing tube.

The vaporizing tube is supplied with a fuel liquid through a supply pipe 30 adapted to be connected with any suitable source of supply. The vaporizing tube is also provided with a valve and clean out rod 31

105

110

operated by a hand wheel 32 the specific construction of which is not a part of this invention but is fully disclosed in my copending application Serial No. 2,825, filed January 16, 1925.

In operating the device the vaporizing tube is initially preheated by igniting in the pan 8 a combustible fluid having a high heat value such, for instance, as alcohol. The flame is deflected upwardly and against the vaporizing tube by the wall 4 and its over-turned ledge 5. This initially heats the liquid fuel sufficiently to vaporize it in the vaporizing tube 28 from which it is emitted into the air mixing device 25 from whence it passes into the gas chamber. As soon as a sufficient amount of gas has been supplied to the gas chamber it is emitted through the perforated discs 20 and 21. The gas emitted through the discs 20 burns within the confines of the refractory radiant frames 23 and the gas emitted through the discs 21 burns within the area of the vaporizing tube so that after the operation of the heater has been initiated by preheating from the flame in the pan 8, it will continue in operation indefinitely and so long as the fuel is supplied to the vaporizing tube 28 through the supply passage 30. The wall 4 constitutes an efficient means for baffling the flame both from the pan 8 and also from the discs 21 so that it is held in close contact with heated area of the vaporizing tube, sufficiently heating it to vaporize the liquid fuel.

I am aware that the invention may be modified in various particulars without departing from the spirit and scope thereof. I do not limit myself unessentially, but what I claim and desire to secure by Letters Patent is:—

1. In a heater the combination with a gas chamber provided with an inclined back wall and parallel series of perforated discs in its upper side, of a vaporizing tube supported above said inclined wall and over one of said series of perforated discs, a pan for containing a liquid located beneath the gas chamber and said inclined wall thereof, and a wall located at one side of said pan and arranged to cooperate with said inclined wall to deflect the flame from the pan against the vaporizing tube.

2. In a heater the combination with a gas chamber provided with parallel series of perforated discs in its upper side and with an inclined back wall below one of said series, of a vaporizing tube supported over said series of perforated discs above said inclined wall, a pan for containing a liquid located beneath the gas chamber and said inclined wall thereof, and a wall located at one side of said pan having an inwardly turned up-

per edge extending over said vaporizing tube and arranged to cooperate with said inclined wall to deflect the flame from the pan against the vaporizing tube.

3. In a heater the combination with a gas chamber provided with parallel series of perforated discs in its upper side and an inclined back wall, of a vaporizing tube supported over one of said series of perforated discs adjacent to the upper edge of said inclined wall, a pan for containing a liquid located beneath the gas chamber and said inclined wall thereof, and a wall located at one side of said pan having an inwardly turned upper edge extending over said vaporizing tube above the plane of said inclined wall and arranged to deflect the flame from the pan against the vaporizing tube, said inwardly turned upper edge being provided with a series of notches centering with the perforated discs beneath the vaporizing tube.

4. In a heater the combination with a gas chamber provided with parallel series of perforated discs and an inclined back wall, of a vaporizing tube supported over one of said series of perforated discs and above said inclined wall, a series of radiant refractory frames supported over the discs of the other series, a pan for containing a liquid located beneath the gas chamber and said inclined wall thereof, and a wall located at one side of said pan and arranged to cooperate with said inclined wall to deflect the flame from the pan against the vaporizing tube.

5. In a heater the combination with a gas chamber provided with parallel series of perforated discs and an inclined back wall, of a vaporizing tube supported over one of said series of perforated discs and above said inclined wall, a pan for containing a liquid located beneath the gas chamber and said inclined wall thereof, a wall located at one side of said pan and arranged to cooperate with said inclined wall to deflect the flame from the pan against the vaporizing tube, and strips of refractory material attached to each face of the upper part of said wall.

6. An oil burner comprising a frame, a pan for containing liquid mounted in said frame, an approximately vertical wall in connection with said frame at the rear side of said pan and having a forwardly extended upper edge, a chamber supported by said frame having a back wall above said pan inclining upwardly and rearwardly toward said first named wall, a series of perforated discs in the upper side of said chamber above the rear portion of said inclined wall, and a vaporizing tube supported over said discs and below the plane of said forwardly curved portion of said first named wall.

CHARLES M. LOEPFE.
